UNITED STATES PATENT OFFICE

LAURENCE ROBERTSON, OF TOLEDO, OHIO

CRANK DISK

Application filed December 16, 1929. Serial No. 414,440.

This invention relates to a crank disk adapted to be driven by a reciprocating piston and the object of the present construction is to facilitate starting from a dead center position. With this end in view, the crank disk, which carries the wrist pin, has a lost motion connection with an adjacent disk secured to the shaft to be driven. The last mentioned disk is driven through the medium of equi-distant dogs or tumblers which are so disposed with relation to the wrist pin as to afford the most appropriate distribution of the load.

The invention will be more particularly described in connection with the accompanying drawings, in which

Figure 1 is a side elevation of the crank disk and the elements associated therewith, parts being broken away.

20 Figure 2 is a section taken on the line 2—2 of Figure 1.

Figure 3 is a section taken on the line 3—3 of Figure 1.

25 Figure 4 is a perspective view of one of the tumblers.

As illustrated in the drawings, the invention is associated with a driven shaft 5 to which a sleeve or hub 6 is secured by a set screw 7 or other suitable means. A disk or 30 wheel 8 is integrally or otherwise secured to the hub 6 and is provided with curved inwardly inclined slots 9 adapted to receive equally spaced tumblers 10 which simultaneously engage the ends of the slots to drive the 35 disk or wheel 8 and thereby rotate the shaft 5.

The tumblers 10 are carried by a crank disk 11 which is mounted on an extension of the hub 6 and which is provided with a wrist pin 12 of any suitable type adapted 40 to be connected with a reciprocating piston by which it is driven. The disks 8 and 11 are connected by a number of rivets 13 which are long enough to permit a relative movement of one disk on the other without binding. One of the disks, as 8, is provided with 45 slots 14 to permit this relative movement.

Each tumbler 10 is formed with a pin 15 which is journaled in the disk 11 and the 50 tumblers may be held in the slots 9 by suit-

able retaining means such as an annular plate 16 secured to the disk 8 by screws 17.

The tumblers 10 are spaced at equal intervals about the center of the disk 11 and when the disk is driven forwardly one pin 55 15 is slightly in advance of the wrist pin 12 while the end of the slot 9 is slightly in advance of the center line through the wrist pin and the shaft 5. The elongated slots 9 permit a lost motion connection between 60 the disks 8 and 11 which facilitates starting from a dead center position and the power which is transmitted from the disk 11 to the disk 8 is equally distributed tangentially about the center of the shaft 5. The construction described makes it possible to start 65 easily from a dead center position, the leverage is uniformly distributed and vibration is eliminated.

While I have shown and described specifically the preferred form of the invention, it is to be understood that the invention includes all such modifications as may fall within the scope of the appended claims.

What I claim is:

1. The combination with a rotatable shaft and a disk secured thereon, of a second disk coaxial with the first disk, a wrist pin secured to the second disk, and a driving connection between the two disks comprising 70 tumblers pinned to one disk, the other disk having slots receiving said tumblers, the slots being longer than the tumblers in a circumferential direction to allow a lost motion between the disks.

2. The combination with a rotatable shaft and a disk secured thereon, of a second disk coaxial with the first disk, a wrist pin secured to the second disk, tumblers pivotally mounted on one disk, the other disk having 80 slots receiving said tumblers, said slots having greater length circumferentially than the tumblers to permit a limited movement of one disk circumferentially on the other.

3. The combination with a rotatable shaft and a disk secured thereon, of a second disk coaxial with the first disk, a wrist pin secured to the second disk, and a driving connection between the two disks comprising 90 pivot pins carried by one disk with tumblers 100

extending forwardly therefrom adjacent one face of the disk and curved inwardly, the other disk having correspondingly shaped slots receiving said tumblers, said slots being longer than the tumblers to allow a lost motion between the disks.

4. The combination with a rotatable shaft and a disk secured thereon, of a second disk coaxial with the first disk, a wrist pin secured to the second disk, tumblers pivotally mounted on the face of one disk which is adjacent the other disk, said tumblers being curved forwardly and inwardly from their pivots, said other disk having slots receiving the tumblers but of greater length than the tumblers to permit a limited movement of one disk circumferentially on the other.

In testimony whereof I have hereunto signed my name to this specification.

LAURENCE ROBERTSON.
